UNITED STATES PATENT OFFICE.

JOSEPH HODGSON, OF PHILADELPHIA, PENNSYLVANIA, ASSIGNOR TO THOMAS DOLAN, OF SAME PLACE.

DESIGN FOR A SHAWL FABRIC.

Specification forming part of Design No. 5,323, dated October 24, 1871.

To all whom it may concern:

Be it known that I, JOSEPH HODGSON, of Philadelphia, county of Philadelphia and State of Pennsylvania, have invented a new and original Design for a Shawl Fabric, of which the following is a specification:

The nature of my design is fully represented in the accompanying drawing to which reference is made.

My design for a shawl fabric is allied to that for which Letters Patent No. 5,106 were granted to me on the 11th day of July, 1871. It differs from that design, however, in one important particular, which will be rendered apparent hereafter.

In the pattern there are a series of stripes, A, alternating with stripes B B of a plaid pattern, each stripe A being composed of a group of minor stripes, the number, size, and color of which may be varied at pleasure. Each stripe B is formed by any combination of longitudinal and transverse minor stripes forming a plaid pattern. D and E are stripes arranged at right angles to each other, so as to form a series of squares, each square, in the present instance, inclosing a portion of one of the stripes A, and a portion of two of the plaid stripes, as shown in the drawing. These stripes D and E are made of silk or other yarn of a brilliant or prominent

character, and appearing on the surface of the woolen fabric impart such brilliancy to the pattern that I have termed them illuminating stripes. In the aforesaid design, patented July 11, 1871, illuminated stripes were shown; but the transverse stripes of silk did not appear on the surface of the stripes A, but were discontinued at the edge of the plaid stripes. In my present design on the contrary the illuminated stripes appear in the surface throughout.

I do not desire to restrict myself to any specific disposal of these illuminating stripes, as the square spaces which they inclose may be varied in size; nor do I restrict myself to the design as applied to a one-faced shawl pattern, as it is equally applicable to a two-faced shawl; but irrespective of the colors employed,

I claim—

The design for a shawl pattern, consisting of plain stripes, alternating with plaid stripes, and having illuminating stripes arranged substantially as described.

In testimony whereof I have signed my name to this specification in the presence of two subscribing witnesses.

JOSEPH HODGSON.
